ROTARY PRINTING PRESS FRAME
STRUCTURE

Emory W. Worthington, Chicago, and Christopher Verne Knell, Glen Ellyn, Ill., assignors to The Goss Printing Press Company, Chicago, Ill., a corporation of Illinois

Application August 14, 1945, Serial No. 610,768

4 Claims. (Cl. 101—180)

1

The present invention relates to rotary printing presses such as are used in newspaper printing, and refers more particularly to a unit frame construction thereof and auxiliary printing roll and inking train supporting members for use therewith.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a side elevation of a press unit frame embodying the invention;

Figure 2 is the same, with the extra equipment of the invention added thereto;

Figure 3 is a phantom side elevation of a portion of Figure 2; and

Figure 4 is a view partly in end elevation and partly in section along the broken line 4—4 of Figure 3.

It is frequently desired to add an extra color printing cylinder to work against one of the impression cylinders of a printing unit, and various frame constructions both of the printing unit and the auxiliary unit have been developed for this purpose. These constructions have usually involved special cap members carrying all the auxiliary equipment, were not very rigid, required removal of all the extra equipment together, and did not permit either the preferred type of impression adjustment in the unit or the preferred oil tight housing surrounding the drive gears of the auxiliary equipment and communicating with corresponding oil tight housing on the unit.

It is an object of the present invention to provide an auxiliary frame for a color cylinder and its associated inking mechanism which shall provide maximum rigidity throughout the en-

larged unit, as well as preferred impression adjustment and preferred oil tight housing of the drive members thereof.

A further object is to provide a press unit frame embodying preferred impression adjustment and lubrication means and adapted to operate either with or without the auxiliary equipment.

A further object is that the auxiliary printing cylinder shall be readily removable from the enlarged unit without the necessity of removing the other auxiliary equipment.

Other objects and advantages will become apparent in the course of the following specification.

In accordance with the illustrative embodiment of the present invention there is provided a press unit the frame members of which have a continuous straight finish across their top portions. Centrally on each side member is located the upper frame member and to either side thereof is a filling block. When it is desired to add a plate cylinder to work against either impression cylinder of the unit, the upper frame member and the filling blocks above that impression cylinder are removed. In place of the upper frame member a special upper frame member carrying the auxiliary fountain and ink train are inserted. The plate cylinder is carried in antifriction bearings preloaded in eccentric cartridges carried in rectangular frame blocks which slip snugly between the unit frame and auxiliary upper frame, engaging horizontal surfaces of both and a vertical surface of the latter, which thereby rests on the unit frame in part directly and in part through the frame block.

The outstanding advantage of the above construction is its rigidity. A further advantage is that preloaded antifriction bearings may be used throughout and impression adjustment is had through eccentric bearing cartridges. A further advantage is that the unit and extra frame members may have a continuous side finish adapted to constitute part of an oil tight housing for use with combined pressure and gravity lubrication of the power transmission system by oil. A further advantage is that the extra plate cylinder may be removed by slipping out the frame blocks, which does not disturb the unit in any way.

It will be understood that the foregoing general

2

description and the following detailed description as well are exemplary and explanatory of the invention but are not restrictive thereof.

Referring now in detail to the illustrative embodiment of the invention as shown in the drawings, the press units comprise side frames 5, 6 surmounted diagonally at their corners by caps 7, 8, 9 and a similar cap not shown, the caps being held on the frames by screws 10 and being effective to mount thereon the bearing cartridges 11 of impression cylinders 12, 13 and the eccentric bearing cartridges 14 of plate cylinders 15, 16. Adjusting screws 14A contact ears 14B formed on cartridges 14 for adjustment of plate cylinders 15, 16 relative to impression cylinders 12, 13. Vibrating ink drums 17 and fountain rolls 18 are gear driven members, as are cylinders 12, 13, 15, 16; the ductor rolls 19 being frictionally driven from the fountain rolls and the unnumbered inking rolls being frictionally driven by the inking drums. Gears on the shafts of the gear driven members, as well as intermediate gears not illustrated are enclosed in oil tight housings 20, 21 placed against the finished side surfaces of the unit frame members 5, 6, communicating with each other at the top of the unit and at the bottom thereof communicating with the housings 22 of the fountain rolls on the bed frame 23 of the unit. The housing system is thus adapted to conduct oil brought by pressure to the gears and bearings of cylinders 12 and 13 and falling by gravity to the lower gears and bearings.

The side frames 5, 6 and caps 7, 8, 9 etc. have a common straight continuous finished surface 24 constituting the top surface of the unit frame proper. Centrally on this top surface on either side of the unit rests a substantially T shaped foot member 25 of the upper framework of the press, separable as at 26 from the remainder of the upper framework 27. Filling blocks 28 rest on the surfaces 24 to either side of foot 25, providing a rounded outer top surface to the unit frame and protecting the finished top surface 24 of the frame proper.

In order to add an extra plate cylinder to the unit, foot 25 and a pair of filling blocks 28 are removed and replaced by the extra equipment. Figure 2 shows an extra plate cylinder 29 added to the unit to work against impression cylinder 12, and it is obvious therefrom that the extra cylinder could just as easily be located so as to work against impression cylinder 13.

Extra frame members 30, 31 which are interchangeable with foot members 25 carry the fountain and ink train for plate cylinder 29. Members 30, 31 have finished surfaces 32 perpendicular to surface 24 and finished surfaces 33 parallel to surfaces 24; the surfaces 24, 32, 33 forming an open rectangle into which frame blocks 34, 35 are slidably and in which they are held by screws 36. Eccentric cartridges 37, adjustable by screws 38, carry the preloaded anti-friction bearings, not illustrated, of plate cylinder 29. The cartridges 37 are recessed to provide surfaces 39 which screws 38 may engage. This permits axial assembly of the solid frame blocks 34, 35 over the cartridges, as compared to cartridges 14 which by reason of the ears 14B require a cap construction.

The exterior side surfaces of the extra frame members 30, 31 and frame blocks 34, 35 are finished and extend in substantially the same vertical plane as the corresponding surfaces of the unit and are thereby adapted to constitute the

inner wall of an oil tight housing system extending from the top of the enlarged unit to the bottom thereof. The components of this system are the long envelopes or housings 40 extending substantially from the top of the extra frame members 30, 31 to the bottom of the half of the unit therebelow, the envelopes 41 communicating therewith and covering the other half of the unit, and the inspection hole covers 42. It is understood that the ink train of cylinder 29 comprises bearings and gears enclosed in housing 40 and similar generally to those of the ink trains of cylinders 15 and 16 and that the cylinders and their inking means may be driven in any convenient manner from a source of power not shown. Oil may thus be applied under pressure to the topmost bearings and gears enclosed in housing 40 and will be conducted by housings 40 and 41 to all other gears and bearings enclosed therein.

The invention in its broader aspects is not limited to the specific mechanisms shown and described but departures may be made therefrom within the scope of the accompanying claims without departing from the principles of the invention and without sacrificing its chief advantages.

What is claimed is:

1. In a press unit comprising side frames and caps diagonally surmounting said frames, in combination, top surfaces formed on said frames and caps and extending continuously thereacross, extra frames supported on said frames, substantially rectangular frame blocks adapted to rotatably support an extra cylinder, said blocks being supported substantially on said top surfaces of said caps, said blocks further having substantially straight and horizontal top surfaces and said extra frames having surfaces adapted to rest on said last mentioned surfaces whereby said extra frames are partly supported through said blocks and caps on said frames.

2. A press unit comprising, in combination, a frame in which a pair of impression cylinders are rotatably mounted near the top thereof, said frame also rotatably supporting the plate cylinders and inking mechanism to cooperate with said impression cylinders, said frame having capped bearing seats for said impression cylinders, the upper portion of said frame and bearing caps providing a continuous, flat, horizontal surface, a footed upper frame secured to said flat surface, said upper frame having a rectangular opening therein over one bearing cap to receive a rectangular frame block rotatably mounting another printing cylinder to cooperate with and be driven with the impression cylinder immediately below said other printing cylinder.

3. A press unit according to claim 2 in which the upper frame has lateral extensions above said other printing cylinder by which the unit may be braced with respect to an adjacent printing unit.

4. A press unit comprising, in combination, an upright main frame having an impression cylinder rotatably mounted at the top thereof so as to permit free access from above, a plate cylinder rotatably mounted below said impression cylinder for running engagement therewith and having an inking mechanism for supplying an ink film, bearing caps secured to said frame at opposite sides thereof to retain the impression cylinder therein, said bearing caps each having a horizontal top surface lying in the same plane, an additional plate cylinder arranged above the

impression cylinder, frame blocks mounted on the horizontal top surfaces of said bearing caps respectively and mounting said additional plate cylinder for running engagement with said impression cylinder, and additional frame means having an inking mechanism for said additional plate cylinder, said additional frame means being attached to the upper portion of said main frame and resting on the upper portion of said frame block.
